(57) **CLAIM**

The ornamental design for a display screen with graphical user interface, as shown and described.

DESCRIPTION

FIG. 1 is a front view of a first image in a sequence for a display screen with graphical user interface according to a first embodiment;

FIG. 2 is a front view of the second image thereof;

FIG. 3 is a front view of the third image thereof;
 FIG. 4 is a front view of a first image in a sequence for a display screen with graphical user interface according to a second embodiment;

FIG. 5 is a front view of the second image thereof; and,
 FIG. 6 is a front view of the third image thereof.

The broken lines and dot-dash showing of the display screen, electronic device and other features form no part of the claimed design. The solid lines shown in a halftone line weight in FIGS. 3 and 6 illustrate portions of the graphical user interfaces that do form a part of the claimed design. In the first embodiment, the appearance of the images includes a sequence or a plurality of transitions, each being from a currently displayed one of the images to one or more of the other images shown in FIGS. 1-3.

In the second embodiment, the appearance of the images includes a sequence or a plurality of transitions, each being from a currently displayed one of the images to either of the other images shown in FIGS. 4-6.

The process or period in which one image transitions to another image forms no part of the claimed design.

The halftone line weight and stippling shown in FIGS. 2, 3, 5 and 6 illustrate a contrast in appearance.
